CLEMENS E. LAPP, OF LOS ANGELES, CALIFORNIA.

APPARATUS FOR REFINING MINERAL OILS.

1,266,281.

Specification of Letters Patent. Patented May 14, 1918.

Application filed November 5, 1917. Serial No. 200,257.

To all whom it may concern:

Be it known that I, CLEMENS E. LAPP, a citizen of the United States, residing at Los Angeles, in the county of Los Angeles and State of California, have invented new and useful Improvements in Apparatus for Refining Mineral Oils, of which the following is a specification.

This invention relates to an apparatus for refining mineral oils.

The principal object of this invention is to provide an apparatus for the distillation of mineral oils which will provide means for continuously treating such oils to successively increasing temperatures whereby the volatile hydrocarbon fluids will be distilled from the oil and will be drawn off at various points along the flow of the oil through the furnace, thus allowing the various grades of 20 light hydrocarbons to be separately and continuously drawn from the liquid as it is treated at different temperatures.

Another object of this invention is to provide an apparatus of the above class through which hydrocarbon oils may be fractionally distilled and which will carry away the hydrocarbon vapors during the distilling operation, and which will reduce carbon deposits to a minimum within the 30 coils of the distilling furnace, thus insuring that the furnace may be operated continuously.

Other objects will appear hereinafter.

The invention is illustrated, by way of example, in the accompanying drawings in which:

Figure 1 is a view in side elevation illustrating the distilling furnace used in the refining apparatus, with parts broken away 40 to more clearly disclose the coils therein and the draw-off pipe leading therefrom.

Fig. 2 is a view in perspective illustrating one of the supporting column elements by which the convolutions of the coil within 45 the furnace are spaced from each other and held in fixed positions.

Referring more particularly to the drawings, 10 indicates a base upon which the cylindrical outer wall 11 of the refining furnace is positioned. This wall incloses a cylindrical heat chamber 12 and a fire box 13 disposed therebeneath. A door 14 is provided through which access to the fire box may be obtained, while a cleaning door 15 is disposed beneath the door 14 to provide draft and allow access to the ash pit of the

fire box. It will be understood that gas or combustible material may be used in the furnace. The upper end of the heat chamber is preferably fitted with a frusto-conical 60 head 16, the apex of which is in communication with a flue pipe 17 through which the products of combustion are drawn off.

Arranged within the heat chamber and concentric with the cylindrical wall thereof 65 is a distilling coil 18 composed of a series of convolutions of pipe disposed in helical fashion adjacent the wall of the chamber and through the center of which hot gases from the fire box may pass. The convolutions of this coil are held in position by supporting columns 19 here shown as composed of separate units 20, as illustrated in Fig. 2. These units are formed with seats 21 and 22 at their opposite ends upon which 70 the adjacent walls of the coil may rest. Rivet holes are formed through the opposite ends of the units so that they may be assembled as shown in Fig. 1 and rigidly held 75 by rivets 23.

The upper end of the coil is fitted with an oil inlet pipe 24 having a control valve 24' which is in communication with a supply tank and is preferably led through a pre-heater of suitable design. The opposite end 85 of the coil is fitted with a draw-off pipe 25 which communicates with a residuum tank into which the residue of the oil is carried.

In order that the hydrocarbon vapors and gases produced by the distillation may be 90 carried off, a series of draw-off pipes 26 are tapped into the coil at various points along its length and extend substantially vertically to provide an escape for these vapors and gases. It will be noted that the temperature 95 within the furnace will decrease as the heat passes upwardly through the coil and away from the fire box. Thus the various convolutions of the coil will be subjected to different degrees of heat and the oil passing through the coil will therefore 100 be caused to give off different grades of hydrocarbons as the oil passes downwardly through the coil. In this manner a hydrocarbon of low boiling point will be drawn 105 off from the top of the coil through one of the pipes 26 and successively heavier grades drawn off through the other pipes 26. These pipes then carry the vapors to a suitable condenser where the vapors are 110 separately condensed. The vapors are condensed in the condensers (not shown) at a rate

which allows the distilling operation to be carried at substantially atmospheric pressures.

The rapidity of the flow of the mineral to be treated may be controlled by valve 24', thus also controlling the temperature of the mineral oil in its passage through the coil 18. The residue may, of course, be subjected to another cycle of treatment through the coil 18, either alone or with untreated mineral oil.

The temperature to which the oil under treatment is subjected may be varied as desired, by the control of the combustion in the furnace and the rate of flow of the oil through the coil 18. I may increase the temperature so that considerable cracking occurs, especially in the lower section of the coil 18. Such higher temperatures may be found desirable when the residue is subjected to a successive treatment.

It will thus be seen that the apparatus here disclosed, while simple in its construction, will operate continuously to refine mineral oils and allow the hydrocarbon vapors and gases to be drawn off in the order they are produced and conveyed away separately.

While I have shown the preferred construction of my apparatus for refining mineral oils as now known to me, it will be understood that various changes in the com-

bination, construction and arrangement of parts may be made by those skilled in the art without departing from the spirit of my invention as claimed.

I claim:

1. In an apparatus for refining oil, a base, a cylindrical wall mounted upon the base, a helical pipe coil mounted vertically within the cylindrical wall; there being supporting columns to engage the convolutions of the coil and hold the convolutions regularly spaced apart, said supporting columns being made up of units fitting together end to end and having seats in their ends to receive the convolutions of the coil; and means for securing the units together.

2. In an apparatus for refining oil, a base, a cylindrical wall mounted upon the base, a helical pipe coil mounted vertically within the cylindrical wall; there being supporting columns to engage the convolutions of the coil and hold the convolutions regularly spaced apart, said supporting columns being made up of units fitting together end to end and having seats in their ends to receive the convolutions of the coil; means for securing the units together, and draw-off pipes leading upwardly from various parts of the coil.

In testimony whereof I have signed my name to this specification.

CLEMENS E. LAPP.
